there tends to be a gravitational displacement of dust from the bottom of said pad.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

An air conditioner for tractor cabs comprising the combination with a substantially enclosed cab of a generally rectangular housing mounted on top of the cab, a vertical partition wall within the housing and disposed intermediate the ends thereof and extending from side to side thereof, the height of such partition wall being substantially less than the height of the housing, a horizontal partition wall lying between the top of the vertical partition wall and one end of the housing and between the sides of the latter, said partition walls dividing the housing into a first chamber and a second chamber, the first chamber lying below the second partition wall and being provided with open air slots in one side thereof, a conduit leading from the second chamber, a suction fan having its intake side in com-

munication with said second chamber and its outlet side opening into the cab, means to drive the fan, the horizontal partition wall comprising a framed filter pad, guide channels within the housing, the housing being provided with a slot in alignment with the channels, the frame of the pad being slidably mounted in said channels, one end of the pad frame being accessible from outside the housing whereby the pad may be removed from the housing.
